UNITED STATES PATENT OFFICE.

WILLIAM A. McGREGOR, OF BRADFORD, PENNSYLVANIA, ASSIGNOR TO McGREGOR WORKING BARREL COMPANY, INC., OF BRADFORD, PENNSYLVANIA.

WORKING BARREL FOR OIL-WELL PUMPS.

1,301,068.

Specification of Letters Patent. Patented Apr. 15, 1919.

Application filed June 17, 1918. Serial No. 240,444.

To all whom it may concern:

Be it known that I, WILLIAM A. McGREGOR, a citizen of the United States, residing at Bradford, in the county of Mc- 5 Kean and State of Pennsylvania, have invented Working Barrels for Oil-Well Pumps, of which the following is a complete specification.

My invention is an improvement in oil 10 well pumps of that particular class in which a working barrel and parts carried thereby, including the pumping mechanism, are lowered into the well tubing to provide a pump-barrel independent of said well 15 tubing which may be removed with the parts it carries for inspection and repair.

My invention contemplates the provision 20 of devices connected to the upper end of the working barrel to assist in holding the latter in place and to prevent sand, broken rivets and other foreign particles from getting into the working barrel to interfere with the operation of the pump-piston or 25 passing down the outside of said working-barrel to its seat.

My invention also contemplates a particular construction of standing-valve for the 30 lower end of the working-barrel and co-operating with the devices at the upper end thereof for firmly and securely holding said working-barrel in the well-tubing to insure a proper operation of the pumping mechanism and to facilitate the removal of the 35 pump for inspection and repair.

With these particular objects in view my 40 invention consists in the construction and arrangement of parts producing an improved working-barrel; all as hereinafter fully described and specifically pointed out in the claims.

In the accompanying drawings:

Figure 1 is a side elevation, partly in 45 section, showing the application of my improved working-barrel and co-operating parts.

Fig. 2 is a sectional view through the 50 working barrel and co-operating parts at the upper and lower ends thereof.

Fig. 3 is a detail view of the bushing in 55 the upper end of the working-barrel.

Fig. 4 is a plan view of the cup-shaped 60 working-barrel retaining device.

Figs. 5, 6, and 7 are views illustrating a 65 modification of the working-barrel retaining device.

Figs. 8, 9 and 10 are views illustrating a second modification of said device.

Referring to the drawings, 15^a and 15^b 70 designate the lower sections of an oil well tubing or casing which are, in the present instance, connected by an interposed short tubular section or coupling 16, the internal diameter of which is less than the internal diameter of the aforesaid sections of the well tubing or casing and the upper end of 75 which is beveled internally, as at 16^a, to form a tapered seat to receive the standing-valve, hereinafter described. This short section or coupling 16 is preferably made of heavy steel to give the required body and 80 stability, and so that the upper end thereof may be ground to provide a smooth hardened seat.

17 designates the removable working-barrel of the pump, in which an ordinary 75 valved pump-piston (not shown) is worked through the intervention of a piston-rod 18, said working-barrel being made either of drawn seamless steel tubing or of brass tubing with a smooth inside finish for the effective 80 operation of the pump-piston therein, and is of slightly less diameter than the internal diameter of the well tubing or casing so that it may be easily lowered thereinto and preferably of greater diameter than the 85 internal diameter of the afore-mentioned coupling 16. Into the upper end of this working-barrel is threaded a bushing 19, having a central upwardly projecting extension 19^a terminating in a head 19^b, the 90 bushing and extension having a vertical bore through which the pump-piston 18 passes, and said bushing is also provided with an annular series of holes 20, around the extension and bore through which the oil or liquid 95 from the working-barrel of the pump passes into the upper part of the well-tubing or casing. The holes or outlets from the working-barrel are closed on the down-stroke of the pump-piston by means of a check-valve 100

21 slidable on the extension 19^a of the bushing, and in the present instance this check-valve is cup-shaped, as shown in the drawings, with the rim extending upward so that the bottom or disk portion will close over 105 the openings in the bushing and the rim will serve to catch broken rivets and other particles which may drop down the well tubing or casing to prevent the same from getting into the working-barrel through the 110

holes 20. It will be noted that the diameter of the cup-shaped check-valve is less than the internal diameter of the well tubing or casing to permit the oil or liquid from the outlet openings or holes 20 to pass around the same.

The working-barrel 17 may be threaded directly on to the lower end of the bushing 20, as shown in Figs. 5 and 6, or coupling devices may be interposed, as shown in Figs. 1 and 2, the latter arrangement providing for the application of the preferred form of the device for retaining the working-barrel, &c. For this purpose a sleeve or coupling 22 is threaded on the bushing and has its lower portion reduced in diameter to receive a second sleeve or coupling 23 threaded on the end thereof; the upper end of the last mentioned sleeve or coupling coöperating 20 with an annular boss 24 on the companion coupling 22 to hold in place a cup-shaped leather ring 25 adapted to fit snugly within the well tubing or casing 15^a to not only firmly hold the working-barrel in place but 25 effectually prevent sand or other particles from passing down between said working-barrel and casing to the seat 16^a on which the standing-valve rests.

The head of the extension on the bushing 30 is cut away at one side to form one part of a coupling device for connecting the piston-rod to said bushing, the other parts of the coupling device being formed by an enlargement on the piston-rod having a downward 35 projection adapted to interlock with the aforesaid head of the bushing when the piston-rod and pump-piston are lowered to their fullest extent; it being understood, of course, that in the operation of the pump 40 the enlargement on the piston-rod reciprocates a suitable distance above its companion coupling member on the bushing.

At the lower end of the working-barrel 17 I provide a standing-valve of particular 45 construction which is adapted in the present instance to coöperate with the cup-shaped leather ring 25 for firmly and securely holding the working-barrel, and the pump, in the well tubing or casing. With this end 50 in view the standing-valve comprises a casting or body portion 27, on the reduced upper end of which is threaded a valve-cage 28 containing a ball 29, and on the lower end of which is threaded a sleeve 30 retaining in 55 place a leather packing 31, the latter being preferably composed of superimposed rings, as shown, and tapered so as to fit snugly within the seat 16^a at the upper end of the section 16' of the well tubing or casing. To 60 receive the leather packing which coöperates with the seat the aforesaid casting or body portion 27 is reduced at its lower end for a considerable portion of its length leaving a shoulder against which the upper end of the 65 packing abuts, and above this shoulder the

casting is tapered, as at 27^a, to provide an auxiliary packing ring which will coöperate with the seat when the leather packing-ring is worn away, said auxiliary packing-ring being of the proper diameter and taper to 70 fit within the upper end of the section 16 of the well casing. The rings forming the leather packing are clamped between the afore-mentioned shoulder and the sleeve which is threaded on the lower end of the 75 casting. The casting and sleeve are bored centrally for the passage of the oil through the standing-valve, and to strain the oil a perforated cap 33 is threaded in the lower end of the sleeve. It will be understood that 80 the leather packing is relied upon to wedge securely within the upper end of the section 16 of the well casing and assist in holding the working-barrel in place, and that the auxiliary packing-ring 27^a comes into play 85 only when the said leather packing is worn away so as to support the working-barrel until it is removed and a new leather-pack- 90 ing applied.

To provide the standing valve with a hard metal seat for the ball 29, a steel ring 32 is let into the lower end of the valve-cage, being held in place between the upper end of the casting and an inwardly-projecting flange on the band forming the lower end of the valve-cage, as shown in Fig. 2.

The modification shown in Figs. 5, 6 and 7 consists in providing the upper part of the bushing 19 with an annular groove 19^d (Fig. 6) in which is seated a packing-ring 35, of 100 leather, fiber, or other suitable material, the upper rim-flange 19^e of said bushing being made a little wider for the purpose; while in the modification shown in Figs. 8, 9 and 10, a composite washer is held in place between 105 the upper end of the working-barrel and rim-flange 19^e on the bushing, in each instance the working barrel being threaded directly on the bushing and consequently the 110 couplings 22 and 23, employed in the construction shown in Figs. 1 and 2, dispensed with. However, the form of ring-packing shown in Figs. 1 and 2 is preferred, as it is more effective in its purpose of holding the 115 barrel and keeping out sand and other small particles.

In the modification in which the packing-ring is clamped between the upper end of the working-barrel and the rim-flange on the bushing (Figs. 8, 9 and 10), said packing-ring is composed of a ring 36 of leather, fiber, or like suitable material, with a reinforcing metal ring 37 at one side having extensions or fingers 37^a which are bent around the outer and upper sides of the leather ring, as shown in Fig. 10, serving to reinforce the leather or fiber portion.

In the operation of my improved working barrel it is lowered into the well tubing or casing by the piston-rod, with the pump- 130

- piston bearing against the underside of the coupling 23 (Figs. 1 and 2) or the bushing 19 (Figs. 5 and 6), and after the standing-valve is seated the piston-rod is pushed 5 down until it is coupled to the bushing and then turned to force the standing-valve or packing thereon tightly into the coupling or section 16 of the well casing and simultaneously expand the coöperating ring-packing 10 at the upper end of the working-barrel into close engagement with the well tubing or casing. Inasmuch as the standing-valve is well seated by the intimate engagement of the packing thereon with the interposed 15 short section 16 of the well casing, and the ring packing at the upper end of the working-barrel is in frictional engagement with the well casing the working-barrel is firmly and securely held against movement during 20 the operation of the pump, and said ring packing in connection with the cup-shaped check-valve will effectively prevent the ingress of particles which might interfere with the proper operation of the apparatus. 25 Although I have shown my improved working-barrel applied to a well casing provided with an interposed section or coupling to form a seat for the standing-valve it will be understood that it may be used in connection with a well having a fixed working-barrel; that is to say, my improved removable working-barrel may be used in place of the old working-barrel, and in such instance it will seat in the upper end of the old working 30 barrel in the same manner as in the interposed short section of the well casing. In either instance I purpose having the external diameter of the removable working-barrel slightly greater than the internal diameter of the standard or fixed working-barrel so as to permit the use of a pump-piston of 35 standard size.
- Having described my invention, I claim:
1. In a well-pump, the combination with a 40 tubing having a section forming an internal seat, of a working-barrel having a packing at its lower end fitting said seat, a bushing at the upper end of the working-barrel having outlet openings and a central extension, a cup-shaped check-valve working on said extension to cover the openings in the bushing, and a ring packing at the upper end of the working-barrel fitting tightly in the well tubing, substantially as shown and for the purpose set forth. 50
  2. In a well pump, the combination with a tubing having a section forming an internal seat, of a working-barrel, a standing-valve secured to the lower end of the working-barrel and having a packing fitting tightly in the upper end of the aforesaid section of the well tubing, a bushing at the upper end of the working-barrel having outlet openings therethrough, and a cup-shaped check-valve on said bushing to close the aforesaid 55 openings. 60
  3. In a well-pump, the combination with a tubing having a section forming an internal seat at its upper end, of a working-barrel supported in the tubing on said seat, a bushing at the upper end of the working-barrel having outlet openings and a central upward extension, and a cup-shaped check-valve 65 slideable on said extension to cover the outlet openings and catch pieces of metal &c., substantially as shown and described. 70
  4. In a well-pump, the combination with a tubing having a seat in the lower portion thereof, a standing-valve threaded in the lower end of the working-barrel, a tapered yielding packing on the standing-valve fitting in the aforesaid seat, an auxiliary packing-ring on the standing valve above said yielding packing, a bushing in the upper end of the working-barrel having openings 75 therethrough and an upward extension, a cup-shaped check-valve on the extension to cover the openings and prevent rivets, &c. entering the same, and a yielding packing-ring at the upper end of the working barrel 80 below the upper end of the aforesaid bushing and fitting within the well tubing. 85

WILLIAM A. McGREGOR.
